AUTOMOBILE HEATING SYSTEM FOR OUT-DOOR DRIVE-IN THEATERS

Gerald A. Behman, San Francisco, and Frank R. Meze, Redwood City, Calif.

Application February 27, 1950, Serial No. 146,574

1 Claim. (Cl. 219—39)

This invention relates to an improved heating system for outdoor automobile drive-in theaters and has for the primary object the provision of a heating system comprising individual, fan-blown coil-heated units positioned in multiple locations and mounted on the conventional posts spaced one from the other, which spaced posts are provided for speakers in outdoor drive-in theaters, said units to be of a suitable wattage commensurable with the particular climate employed and line-operated from existing source of electric supply in the outdoor drive-in theater, each unit being provided with a conventional coin-control means for electrically starting the heater and with suitable switches for connection and disconnection of the same by the user.

Another object of the present invention is the provision of a bar or other suitable means on the post for retaining the heater thereon when not in use.

A further object of the present invention is the provision of a specially constructed bracket on the heater for enabling the same to be suspended on the window sill or lowered window of the automobile.

A still further object of the present invention is to form a series of vents in the heater casing and to provide angular shaped fins for directing the blown air downwardly and through the inside of the car.

A still further object of the present invention is the provision of a heating system and unit for outdoor automobile drive-in theaters that is durable, simple in construction, positive in operation, economical to manufacture and highly efficient and serviceable in use.

Other objects and advantages will be apparent during the course of the following description.

In the accompanying drawing forming a part of the specification wherein for the purpose of illustration like numerals designate like parts throughout the same,

Fig. 1 is a schematic diagram showing a plurality of posts and the heating units associated therewith and an enlarged diagrammatic view of one of the heating units connected to the electric supply line,

Fig. 2 is a vertical elevational view of a conventional post employed in outdoor drive-in theaters for carrying the speakers and shows two heaters, one of which is suspended on each side of the post,

Fig. 3 is a vertical view, shown partly in elevation and partly in section, of one of the specially constructed heaters employed in the invention,

Fig. 4 is a bottom plan view of the same, and Fig. 5 is a circuit diagram employed in conjunction with relay coil in coin control box.

Referring in detail to the drawing and numerals thereof the numeral 7 designates one of a series of posts employed in an outdoor drive-in theater for carrying the speakers 8 and 9 as disclosed to advantage in Fig. 2. The numerals 10 and 11 designate two bars, one of which extends from each side of the post and is fixed thereto in any suitable manner and is provided for suspending a heater on each side of the post. The numeral 12 designates the coin control box for accommodating two relays 13 as shown in Fig. 5, one relay of which is operated when a coin is put in the drop 14 for starting the heater positioned on the right side of the post and the second relay operated when a coin is put in the drop 15 for starting the heater positioned on the left side of the post. The coin control mechanism is of conventional construction well known in the art, the details of which are not described as the specific construction of the said mechanism is not considered a part of the invention.

The heater is designated as a whole by the numeral 16 and comprises a casing 17 of any suitable size or shape and into which is provided, at the top portion thereof, an electric motor 18 secured to the top by bolts or rivets 19. A fan 20 is fixed on the motor shaft 21 for blowing air across the heating coil 22. The bottom of the casing is formed with a circular opening 23 and a series of fins 24 are positioned across the opening and welded or otherwise fixed to the casing in any suitable manner, whereby a series of vents 25 are formed for enabling the warm air to be blown from the housing. The said fins extend at a suitable angle inwardly as disclosed to advantage in Fig. 3 to properly direct the warm air into the car. A specially constructed bracket 26, preferably in the form of an inverted U, is fixed to the upper outer side face of the casing as illustrated in Fig. 3 to provide a suitable medium for suspending the heater on the window sill 27 of the car, which window sill is illustrated in dot and dash lines. However, the window of the car could be lowered a short distance and the heater suspended on the same if desired.

In Fig. 1 there is shown for illustrative purposes the main supply line for the heating units and is designated by the conductors 28 and 29, the said line preferably carrying 110 volts, alternating current, and is provided with a master switch 30. A conductor 31 leads from the motor

18 to a suitable switch 32 and a second conductor 33 leads from the said switch to the supply line conductor 28 and a third conductor 34 leads from the motor to the line 29. The numeral 35 designates a conductor leading from the heating coil 22 to the conductor 34, a second conductor 36 is connected to a second switch 37, which switch is connected to the line 28 through switch 32 and conductor 33, completing the circuit. A suitable resistance coil 38 is provided in said circuit. A three way switch "high," "low" and "off" may be employed or any other type of switch desired.

Having thus described our invention, we claim:

A device of the character described for heating automobiles in outdoor theatres and like places comprising an electric heater, embodying in its construction a housing, a bracket in the form of an inverted U-shaped member for removably suspending said housing from the window sill of the automobile, an electric heating

coil positioned in said housing, a motor mounted in said housing in the rear of said heating coil, a revolvable fan connected to the motor and adapted to blow air past the heating coil, and means including a series of openings in one of the walls of the housing and a series of angularly positioned fans associated with the openings for dispensing and guiding the blown air to and within the housing.
